The ornamental design for an engine shipping mount with adjustable slider insert, as shown and described.

DESCRIPTION

FIG. 1 is a top front right side perspective view of the engine shipping mount with adjustable insert of this design;

FIG. 2 is a front view thereof;

FIG. 3 is a left side elevational view thereof;

FIG. 4 is a top plan view thereof;

FIG. 5 is a right side elevational view of the apparatus of this design;

FIG. 6 is a bottom plan view thereof;

FIG. 7 is a rear elevational view of the engine shipping mount of this design;

FIG. 8 is an above front left exploded view of the two components of this design; and,

FIG. 9 is a below rear right exploded view of the two components of this design.

In FIGS. 1-7 inclusive, the insert component is shown in portion.

The broken line showing of an engine in FIG. 1 is for illustrative purposes only and forms no part of the claimed design.
